PUTTY REMOVER

Frank Pomichter, Cold Brook, N.Y.

Application July 16, 1947, Serial No. 761,183

5 Claims. (Cl. 30—172)

1

My invention relates to a putty remover, and I declare the following to be a full, clear, concise and exact description thereof sufficient to enable anyone skilled in the art to which it appertains to make and use the same, reference being had to the accompanying drawings in which like characters refer to like parts throughout.

The object of the invention is to provide a device that will remove putty from the wooden frame bars between the panes of glass used in roofing greenhouses. To this latter end the device is constructed to straddle the bar that separates the panes in the window, whereby to remove the putty from both sides simultaneously. The device will be found useful also in removing the putty from the frame bars between the panes and from the edges of the window sash.

The object will be understood by referring to the drawings in which

Fig. 1 shows a perspective view of the device.

Fig. 2 shows a perspective view looking at the side opposite to that shown in Fig. 1.

Fig. 3 is a vertical section taken on the line 3—3 of Fig. 4.

Fig. 4 is a plan view looking up from beneath.

Fig. 5 is a detail view showing certain parts of the device.

Fig. 6 is a detail view showing a perspective of one of the knives embodied in the device.

Fig. 7 is a detail view showing a perspective of a member for holding a knife in position.

Referring more particularly to the drawings, the putty remover embodies a pair of runners 1, 1 which are held in parallel spaced relation by a plate 2 having laterally extending sides 3, 3 and an upstanding channel member 4. The upper surfaces of runners 1, 1 are formed with counter-sunk recesses for holding the upper surface of flanges 3, 3 flush with the upper surface of runners 1, 1. Plate 2 is provided with recesses 5, 5 made in laterally projecting members 3, 3 for the reception of screw bolts 6, 6 which are threaded into bores in runners 1, 1. Each of the bolts 6, 6 is provided with a head 7 having a counter-sunk angular recess 8 for the application of a socket wrench, not shown. The said bolts 6, 6 hold plate 2 in rigid adjusted position to runners 1, 1.

The forward part of each of the runners 1, 1 is beveled at 10 and recessed at 11 for the reception of angle shaped knives 15, 15. Each of the knives 15, 15 is held to the runners 1 by a half circular member 20, which rests in a counter-sunk recess 21 on the inside surface of run-

ner 1. Each of the members 20, 20 is held in position by a bolt 22 having a socket head 23 for the application of a socket wrench. Furthermore, each of the members 20 has an offset part 24 that engages a groove 25 formed in each of the knives 15, whereby to hold said knives 15, 15 in position.

The rear end of each of the runners 1, 1 has lateral recesses for the partial reception of rollers 30 having reduced ends that provide shafts having bearings in the contiguous parts of runners 1, 1. The outer peripheral surfaces of rollers 30, 30 are in line with the outer edges 32, 32 of knives 15, 15, whereby to hold said knives 15, 15 in maximum cutting position. Said rollers 30 also aid in reducing friction.

The means for limiting the lower most position to which the knives 15, 15 can descend on either side of the bar of the window sash embodies a roller 35 mounted to turn on a shaft 36 carried in bearings in the bifurcated end 37 of lever arm 38.

Lever arm 38 is pivoted to turn on a shaft 40 carried in bearings in opposite sides of the channel member 4 of plate 2. The means for limiting the upward swing of lever arm 38 embodies a headed screw bolt 41 having a threaded aperture in the top part of channel member 4. It also projects down through plate 42 of the handle 43, hereinafter mentioned. A lock nut 45 is mounted on said bolt 41 to hold said bolt 41 in adjusted position. Lock nut 45 has vertical recesses for the application of a spanner wrench, not shown.

Handle 43 comprises gripping part 50 and plate 42 bent to form substantially a V. The upper end of plate 42 is held to the beveled flat surface 51 of grip 50 by a headed screw bolt 52. The lower part of plate 42 is held to the lower flat surface of grip 50 by screw bolt 53 that engages a threaded recess in the upper surface of channel member 4. It is held also by screw 54 projecting upward through plate 42 into grip 50. A screw bolt 55 projects through plate 42 and engages a threaded aperture in the upper surface of channel member 4 of plate 2, whereby to hold said handle 43 thereto.

The means for allowing one of the runners 1 to yield laterally with respect to the other, whereby to anticipate variation in the thickness of the putty to be removed from the sides of the bar of the window pane contemplates the lateral sliding motion of one of the runners 1 on one of the flanges 3 of plate 2. To this end a bar 60 is bolted at 61, 61 to runner 1 across

the flange 3, whereby to hold said flange in the counter-sunk recess formed in the top surface of runner 1. Bolts 63, 63 are rigidly mounted in one of the runners 1 and project laterally therefrom and through an angle plate 64 having loose apertures therefor. Headed nuts 65, 65 with knurled surfaces are threaded to the outer free ends of bolts 63, 63. Said nuts 65, 65 are held in predetermined position by lock nuts 66 having vertical grooves for the application of a spanner wrench. Furthermore, plate 64 is held to flange 3 by screws 67 engaging threaded bores in said flange 3. Coil springs 68 are mounted on bolts 63. One end of said springs 68 rests in a counter-sunk recess in the side of runner 1 and the other end rests against the inner surface of plate 64, whereby to yieldingly hold said runners 1 in given relation to the other runner 1.

The operation of the device is effected by adjusting the roller 35 with relation to the lower surface of knives 15, 15 by turning bolt 44, whereby to limit the upward swing of lever 38. This adjustment of roller 35 will limit the depth to which knives 15, 15 can descend to cut the putty and yet not exert an abnormal pressure on the window pane. Knives 15, 15 are mounted in the front ends of runners 1, 1 with the half circular member 20 engaging the grooves 25 in said knives 15, 15 and then tightening screws 22, 22. The device can then be placed with the runners spanning the bars of the window frame and the device moved therealong, whereby the knives 14 will cut the putty on either side of said bar, and yet not break the window pane. In the event an obstruction or abnormally wide portion is reached one of the runners 1 will yield laterally under pressure of springs 68.

In the event that user wishes to cut the putty along the inner edge of the window sash he may use one of the knives 15 and slightly turning the device at an angle.

Having thus described my invention, what I claim as new and desire to secure by Letters Patent is as follows:

1. In a putty remover, runners held in spaced parallel relation to each other, whereby to span the bar of a window frame, knives detachably mounted to said runners for removing the putty from the sides of said bar, members attached to said runners for holding said knives thereto and one of said runners mounted to move relative to the other, whereby to allow for a given amount of yield.

2. In a putty remover, a pair of runners held

in spaced relation to each other, a plate member for holding said runners in adjustable position relative to each other, knives removably mounted to said runners for scraping putty from a window bar, and a lever having a roller mounted thereto attached to said plate for holding the knives in given relation to the window bar.

3. In a putty remover, a pair of runners, a plate member detachably mounted to said runners for allowing one of said runners to be held adjustably to said plate member, knives removably mounted to said runners, a lever having a roller mounted therein attached to said plate member, whereby to hold said knives in pre-determined relation to a window pane, and a handle attached to said plate member for moving said putty remover.

4. In a putty remover, a pair of runners, a plate member detachably mounted to said runners, flanges formed on said plate, an angle member mounted to one of said flanges, bolts mounted to said runners and projecting through said angle plate, springs mounted on said bolts between said runners and said angle plate for allowing one of said runners to be held in pre-determined relation to said plate member, knives removably mounted to said runners, a lever having a roller mounted therein attached to said plate member, whereby to hold said knives in pre-determined relation to window pane, and half circular members mounted in said runners to hold said knives in given relation to the putty.

5. In a putty remover, a pair of runners, a plate member detachably mounted to said runners, means for allowing one of said runners to be held in pre-determined relation to said plate member, knives removably mounted to said runners, a lever having a roller mounted therein pivotally attached to said plate member, whereby to hold said knives in predetermined relation to window pane, and rollers mounted in said runners to hold said knives in given relation to the putty.

FRANK POMICHTER.
